UNITED STATES PATENT OFFICE.

EDWIN R. McMASTER, OF BUFFALO, NEW YORK.

DESIGN FOR A MEDAL.

SPECIFICATION forming part of Design No. 31,388, dated August 15, 1899.

Application filed July 22, 1899. Serial No. 724,870. Term of patent 3½ years.

To all whom it may concern:

Be it known that I, EDWIN R. McMASTER, a citizen of the United States, residing at Buffalo, in the county of Erie and State of New York, have invented and produced a new and original Design for a Medal, of which the following is a specification.

The invention relates to a new and original design for a medal; and it has for its object to provide a design of this character which will be ornamental and attractive.

The essential feature of the design resides in a medal having a representation of the map of North and South America on one face and provided on its other face with an American eagle, the head of a buffalo, and the figure of a woman with an American flag in one hand and a pair of scales in her other hand.

In the drawings, Figure 1 is an elevation showing one face of the medal. Fig. 2 is a similar view showing the other face of the same.

Referring to the drawings, 1 designates a circular body provided at the center of its front face 2 with the figure of a woman and having the head 3 of a buffalo arranged be-

neath the figure of the woman. The figure or representation 4 of the woman has an American flag 5 in one hand and has the other arm extending and supporting a pair of scales 6. 30 The front face of the medal is provided with an American eagle 7, arranged at the top of the medal and having its wings and head extended beyond the periphery of the body of the medal. The rear face of the medal is provided with a map 8 of North and South America, and a series of ships 9 is scattered around the map. A scroll 10 is arranged beneath the eagle, on the front face of the medal, and the said scroll and the front and rear faces 2 and 11 are designed to bear suitable inscriptions. 35 40

What is claimed is—

The design for a medal, herein shown and described.

In testimony that I claim the foregoing as my own I have hereto affixed my signature in the presence of two witnesses.
